UNITED STATES PATENT OFFICE.

WALTER P. MURPHY, OF CHICAGO, ILLINOIS.

CAR-ROOF.

1,115,090.

Specification of Letters Patent. Patented Oct. 27, 1914.

Application filed July 31, 1912. Serial No. 712,428.

To all whom it may concern:

Be it known that I, WALTER P. MURPHY, a citizen of the United States, and a resident of the city of Chicago, in the county of Cook and State of Illinois, have invented a new and useful Improvement in Car-Roofs, of which the following is a specification.

This invention relates to car roofs and more particularly to outside metal roofs.

It has for its principal objects to improve upon the construction and arrangement of the roof and of the fastening means for the roofing sheets in the region of the eaves; to provide for considerable radial movement of the roof in order to compensate for the weaving and racking motion of the car body and thereby prevent the concentration of stresses which tend to tear the sheets; to provide for mounting the securing clips or hood castings on top of the roof entirely within the side lines of the car body and without perforating the roofing sheets proper; to obviate the necessity for providing a fascia or protective molding along the sides of the car body at the eaves; and to attain certain other advantages which will hereinafter more fully appear.

The invention consists in the parts and in the arrangements and combinations of parts hereinafter described and claimed.

In the accompanying drawings which form part of the specification and wherein like symbols refer to like parts wherever they occur:—Figure 1 is a fragmentary view, showing in elevation, a portion of a car body in the region of the eaves and also adjacent to a roof seam; Fig. 2 is a vertical section taken on or about the line 2—2, of Fig. 1; Fig. 3 is a vertical section taken on or about the line 3—3, of Fig. 1; Fig. 4 is a fragmentary perspective view of the portions of two roofing sheets adjacent to the eaves margins and side seam, and also showing the coöperating flashing sheets and joint shield; Fig. 5 is a perspective view of a hood casting detached; Fig. 6 is a fragmentary view, in section, showing how the flanged perforations in the flashing sheets coöperate with the flanged bolt holes in the hood casting; Fig. 7 is a view similar to Fig. 2 showing a modification of the roofing and flashing sheets; Fig. 8 is a perspective view of the flashing sheet of the structure shown in Fig. 7; and Fig. 9 is a perspective view of the flashing joint shield.

The wooden substructure of the roof com-

prises a side plate 1 to which the side sheathing 2 is secured, and a supplemental plate or filler 3 which is inserted between the top of the side plate proper and wooden sheathing 4 of the roof, and extends over the side sheathing 2 so as to be flush with the outer face of the latter. The wooden roof sheathing is rabbeted or grooved for a considerable distance inward from the eaves to accommodate the rebent marginal portions of the metal roofing sheets and co-operating portions of the eaves flashing in order to allow the end portions of the roofing sheets to lie in the same plane as the body portions, which latter rest on the wooden sheathing, as will be hereinafter more fully set forth.

Referring now more particularly to the structure shown in Figs. 1 to 4, inclusive, the metal roofing sheets 5 are shown connected by high seams 6 made by overlapping rebent marginal portions of the sheets. The eaves ends of the sheets are turned under, and the doubled under portions coöperate with the turned over inner marginal portions 8 of flashing sheets 9.

The flashing sheets 9 rest on cutaway or rabbeted portions of the wooden sheathing 4 and they are turned down over the eaves, the turned down portions 10 being nailed or otherwise fastened to the side sheathing 2. These flashing sheets, as shown in Figs. 1 and 4, are made to abut at their ends, and adjacent to the joints they are corrugated or provided with pressed-up hollow ribs 11 which extend crosswise of their middle lengths. These hollow ribs stiffen the flashing and also support the end portions 7 of the roofing sheets proper. Under the flashings, at each joint, is placed a shield 12 whose inner and two side margins 13 are flanged up slightly, and whose outer end portion 14 is turned down over the eaves and nailed or otherwise secured to the side of the car. This shield is preferably of such width that its side flanges 13 lie under the hollow ribs or corrugations 11; and its length is such that the inner end flange lies beyond the inner end of the flashing.

Securing clips or "hood castings" 15 are mounted on the roof at the eaves corners of the roof sheets to coöperate with the end portions of the raised side seams thereof. The hood portion of each casting is arranged so as to straddle the seam and cover its open end, and is normally out of contact

therewith on all sides. The side flanges 16 of the securing clips are preferably concavo-convex in cross section, and are normally in contact with the roofing sheets on opposite sides of the seam. The hood casting has a flat base or supporting plate 17 which rests flatwise on top of the eaves flashing. This base portion 17 is pierced with two tapered holes 18 through which lag screws or bolts 19 are inserted into the wooden substructure of the roof. As shown in the drawings, the lag screws are passed through the wooden sheathing 4 and into the supplemental side plate 3. The holes 18 are smallest at the top, and there are flanges surrounding their tops. To strengthen the hood casting the side flanges 16 are extended outward beyond the hood portion and are turned down where they join the base or supporting portion 17, forming end walls 16^a. The perforations in the flashing sheets 9 and joint shield 12 are flanged upward, forming sloping walls 20 which project into the tapered perforations 18 in the hood casting base and prevent water from penetrating the roof covering by following the lag screws or bolts which fasten the hood casting upon the roof.

By placing the hood casting on top of the roof, entirely within the side lines of the car body as shown, the fascia or eaves molding may be eliminated as there are no projections to be guarded in case the cars "side scrape". So, too, by doing away with the fascia or eaves molding there is more clearance at the top of the car, and the cars are less liable to "side scrape". Further advantages of the construction are that no holes need to be made in the roofing sheets proper in order to fasten them to the substructure, and the roof is securely held against undue displacement and at the same time it has enough flexibility and capacity for movement to compensate for the "weaving" and "racking" of the car body.

In the structure shown in Figs. 1 to 4, inclusive, the corrugations or ribs 11, extend from the inner margins of the flashing sheets 9 entirely to the eaves, but in the modification illustrated in Figs. 7 and 8, the corrugations or ribs 11^a extend only for a distance sufficient to support the rebent ends of the roofing sheets, the portion of the flashing adjacent to the eaves being left flat to receive the base portion 17 of the hood casting. In this modification, the flashing sheets are made to overlap at their joints so that the corrugations 11^a of the adjoining sheets fit the one within the other. In this construction the shield 12 may or may not be used, as desired. However, it is preferable to provide it as shown in Fig. 7. The flashing 9^a illustrated in Figs. 7 and 8 is merely flanged upward along its inner margin 21, instead of being rebent; and, in

lieu of rebending, a supplemental flashing strip 22 is nailed along the wooden roof sheathing adjacent to the rabbet so as to overhang the rebends 7 of the roofing sheets.

Obviously, the structure admits of considerable modification without departing from the invention. Therefore, I do not wish to be limited to the specific construction and arrangement shown.

What I claim is:

1. A car roof comprising movably secured metal roofing sheets mounted on the substructure and whose ends terminate short of the eaves, flashing strips mounted on the substructure in the region of the eaves and whose inner marginal portions coöperate with the end portions of the roofing sheets proper to make a weatherproof joint, securing clips having base portions resting on said flashing strips and located entirely within the side lines of the car but spaced from the ends of the roofing sheets and having extensions overhanging and retaining said roofing sheets, and fastening means secured in the roof substructure and clamping the base portions of said securing clips on said flashing strips.

2. A car roof comprising a substructure, a metal roof sheet resting on said substructure and terminating short of the eaves, the end portion of said roof sheet adjacent to the eaves being turned back under the body of the sheet and spaced therefrom, an eaves flashing sheet resting on the substructure and having its outer marginal portion turned down over the eaves and secured to the side of the car, its inner marginal portion being loose and extending upward underneath said roof sheet, and a second flashing sheet secured along one edge on the substructure under the roofing sheet proper and with its other edge lapping over the turned under end portion thereof, said second flashing sheet also lapping over the inner portion of said first-mentioned eaves flashing sheet.

3. A car roof comprising wooden sheathing, said sheathing being rabbeted adjacent to the eaves, metal roofing sheets resting on said sheathing, the end portions of said roofing sheets being turned back under the body and spaced therefrom and overhanging the rabbeted portion of the wooden sheathing, flashing sheets resting on said rabbeted portion of the sheathing, the outer marginal portions of the flashing sheets being turned down over the eaves and secured to the side of the car and the inner marginal portions being flanged upward, and a flashing strip secured flatwise on the roof sheathing adjacent to the rabbeted portion thereof and overhanging the same, and loosely engaging the turned under end portions of the roofing sheets proper whereby the latter are movably secured upon the roof independently of said flashing sheets.

4. An outside metal car roof comprising adjoining roofing sheets proper whose ends terminate short of the eaves, eaves flashing sheets resting on top of the roof substructure and underlying and slidably engaging the end portions of said roofing sheets proper, and joint flashing sheets underlying the adjoining end portions of said eaves flashing sheets and the end portions of said roofing sheets proper.

5. An outside metal car roof comprising adjoining roofing sheets proper whose ends terminate short of the eaves, flashing sheets resting on top of the roof substructure adjacent to the eaves and turned down over the eaves and secured to the side of the car, the inner portions of said flashing sheets underlying and slidably engaging the end portions of said roofing sheets proper; and joint flashing sheets underlying the adjacent end portions of said first mentioned flashing sheets and the end portions of said roofing sheets proper.

6. An outside metal car roof comprising adjoining roofing sheets proper whose ends terminate short of the eaves, flashing sheets resting on top of the roof substructure adjacent to the eaves and turned down over eaves and secured to the side of the car, the inner portions of said flashing sheets underlying and slidably engaging the end portions of said roofing sheets proper, and joint flashing sheets underlying the adjoining end portions of said first mentioned flashing sheets and extending beyond the inner margins thereof, the side and inner end margins of said joint flashing sheets being turned upward.

7. An outside metal car roof comprising adjoining roofing sheets proper, eaves flashing sheets underlying and slidably engaging the end portions of said roofing sheets proper and being provided with raised hollow transverse ribs near their ends which also underlie the said roofing sheets proper, and joint flashing sheets underlying the meeting end portions of said eaves

flashing sheets and extending beyond the inner margins thereof, the side marginal portions of said joint flashing sheets being turned upward in the region of said raised hollow transverse ribs of the eaves flashing sheets.

8. A securing clip for outside metal car roofs, said clip comprising a flat base adapted to rest on the roof adjacent to the end of a roofing sheet and an upwardly offset lateral extension parallel to said base and adapted to overhang the roofing sheet, said base having a bolt opening therethrough which is wider adjacent to the underside of the base than at the top thereof.

9. A securing clip for outside metal car roofs, said clip comprising a flat base adapted to rest on the roof adjacent to the end of a roofing sheet and an upwardly offset lateral extension parallel to said base and adapted to overhang the roofing sheet, said base having an opening therethrough which is surrounded by a tapered upstanding flange on the upper side of the base.

10. A securing clip for car roofs comprising a flat base portion adapted to be secured on top of the roof, an upwardly offset hood extension adapted to overhang the end portion of the roofing sheet, and lateral flanges extending along the lower edges of said hood extension and joining in a downward bend with said base portion beyond the end of said hood extension.

11. A securing clip for car roofs comprising a base portion adapted to be secured on top of the roof, an upwardly offset lateral hood extension and lateral flanges extending along the lower edge of said hood extension in a plane above the base portion, said flanges merging with the base portion inward from said hood extension.

Signed at New York city, N. Y., this 20 day of July 1912.

WALTER P. MURPHY.
